CLAIM

The ornamental design for a steam generator for a steam iron, as shown.

DESCRIPTION

FIG. 1 is a front perspective view of the steam generator for a steam iron of the present invention;

FIG. 2 is a rear perspective view of the steam generator for a steam iron of FIG. 1;

FIG. 3 is a side view in elevation of the steam generator for a steam iron of FIG. 1 as seen from the left-hand side of FIG. 5;

FIG. 4 is a side view in elevation of the steam generator for a steam iron of FIG. 1 as seen from the right-hand side of FIG. 5;

FIG. 5 is a front view in elevation of the steam generator for a steam iron of FIG. 1;

FIG. 6 is a rear view in elevation of the steam generator for a steam iron of FIG. 1;

FIG. 7 is a top plan view of FIG. 6; and

FIG. 8 is a bottom view of FIG. 6.
